UNITED STATES PATENT OFFICE

2,441,427

SPIN VANE CONTROL FOR FANS

Roland L. Lincoln, Dover, Mass., assignor, by
means assignments, to Westinghouse Electric
Corporation, a corporation of Pennsylvania

Application October 22, 1945, Serial No. 623,800

5 Claims. (Cl. 238—114)

1

This invention relates to fans, and relates more particularly to fans with spin vanes in their inlets for adjusting the volumes of gas passing through the fans.

The H. F. Hagen, U. S. Patent No. 1,846,863, discloses the use of spin vanes with centrifugal fans for varying the gas volumes handled thereby with corresponding variations in the power consumed. It is necessary to use a large number of vanes for providing the desired result, and to rotate all vanes simultaneously with a single control. The vane adjusting mechanisms require servicing from time to time, and with the prior constructions it has been difficult for a service man in the field to obtain access to the adjusting mechanisms and to adjust and replace same.

An object of this invention is to provide spin vane controls for fans, which are more readily accessible for servicing than the prior controls.

Other objects of the invention are to simplify spin vane controls for fans, and to reduce their cost.

The invention will now be described with reference to the drawing, of which:

Fig. 1 is a side elevation with portions in dashed outline, of a double inlet centrifugal fan embodying this invention;

Fig. 2 is an end view with a portion of an end wall removed, of the fan of Fig. 1;

Fig. 3 is an enlarged view in section, of the fan wheel and one of the scroll inlets of the fan;

Fig. 4 is an end view of three of the vane adjusting members, with the vanes shown in dashed outline midway between open and closed positions;

Fig. 5 is an end view of one of the vane adjusting members with its associated vane shown in dashed outline in open position;

Fig. 6 is an end view of one of the vane adjusting members with its associated vane shown in dashed outline in closed position, and

Fig. 7 is a plan view looking downwardly upon one of the resilient strips used for connecting the different vane adjusting members to a common adjusting ring.

The fan illustrated has the wheel 10, the scroll outlet 11, and the two opposite scroll inlets 12. The wheel 10 is mounted on the shaft 13 which is supported in the two bearings 14, and rotated by the constant speed, electric motor 15.

Each scroll inlet 12 has the curved vanes 16 which are pivoted on the studs 17 which, in turn, are spaced equal distances apart and arranged on the circumference of a circle concentric with

2

the inlets of the wheel 10. The inlet scrolls 12 are connected by the ducts 18 to a common gas source.

The construction described in the foregoing 5 is conventional and essentially that disclosed in said Hagen patent. The novel features added by this invention will be described in the following.

The cam levers 20 are attached to the vanes 16, and rotate about the pivot studs 17. The cams 20 have the curved outer surfaces 21 which contact the inner surfaces of the strips 23, and which may be formed as circular arcs with centers at the centers of the studs 17, or may have other curvatures as will be described. Each lever 20 has a tapped opening adjacent one end of its surface 21 for receiving the machine screw 22.

The strips 23 are of spring metal and have the slots 24 formed therein adjacent corresponding ends thereof, and have the circular openings 25 adjacent their opposite ends. The strips 23 are attached to the rings 26 by the rivets 27 in the openings 25.

The machine screws 22 extend through the slots 24 and are threaded into the tapped openings in the levers 20 described in the foregoing, and serve to attach one end of each of the strips 23 to one of the levers 20, the other end of each of the strips 23 being attached to one of the rings 26 as previously described.

30 The rings 26 are rotatably supported on the rollers 30 which in turn, are rotatably mounted on the studs 31 which are attached to the end walls 32 of the fan. Each ring 26 has a gear segment 34 formed thereon and which meshes with the worm gear 35 attached to the shaft 36. There are two shafts 36, one for each ring 26, and these shafts have the bevel gears 37 attached thereto. The gears 37 mesh with the bevel gears 38 which are attached to the shaft 39 on which is mounted the control wheel 40 which may be used for rotating the rings 26.

Rotation of the hand wheel 40 causes through the bevel gears 37 and 38, the worm gears 35 and the gear segments 34, the rings 26 to rotate. 45 When one of the rings 26 is rotated in a clockwise direction with respect to Figs. 2, 4, 5 and 6, it adjusts its associated vanes 16 towards closed positions by moving the strips 23 in a clockwise direction against the levers 20 which, in turn, rotate the vanes 16 in a clockwise direction towards closed positions.

When one of the rings 26 is rotated by the hand wheel 40 in a counterclockwise direction with respect to Figs. 2, 4, 5 and 6 of the drawing, the 50 strips 23 pull the levers 20 in a counterclockwise

direction and cause the vanes 18 to be rotated towards open positions.

Fig. 5 illustrates a vane 18 in wide open position, and Fig. 6 illustrates the vane in fully closed position. In wide open positions the vanes 18 have no spin inducing effect on the air or other gas handled by the fan. As the vanes are moved towards closed positions, the spin they impart to the gas entering the fan is increased, the increase in spin causing reduced gas pressures and volumes as disclosed in detail in said Hagen patent.

The curved inner surface of the rings 26, and the curved outer surfaces 21 of the levers 28 cooperate to prevent undesired deformation of the strips. As illustrated by Figs. 4, 5 and 6, as the strips 23 are moved to adjust the vanes 18 to different positions, large portions of their surfaces are pressed against the inner surfaces of the rings 26 or are wrapped against the outer surfaces 21 of the levers 28. This prevents buckling of the strips.

The curved surfaces 21 of the levers 28 may be cam surfaces shaped to provide a uniform rate of adjustment of the vanes, or may be shaped to provide non-uniform rates of adjustment if this is desired.

The positions of individual vanes can be adjusted by loosening the screws 22 and adjusting same along the slots 24. Due at times to the deformation of the fan casing, such adjustments are desirable for preventing binding of the mechanisms.

As illustrated by the drawing, the vane moving mechanisms are on the exterior of the fan casing, and are readily accessible for servicing and replacement.

Other advantages of the present construction are that there is less friction, less lost motion due to back lash, and the mechanism is less expensive to manufacture and to install.

While one embodiment of the invention has been described for the purpose of illustration, it should be understood that the invention is not limited to the exact apparatus and arrangement illustrated as modifications thereof may be suggested by those skilled in the art, without departure from the essence of the invention.

What is claimed is:

1. In a fan having a rotor, an inlet to said rotor and a plurality of spin vanes pivoted in said inlet, the combination of levers attached to said vanes, a ring, a plurality of resilient strips, means attaching said strips adjacent their ends to said levers and to said ring, said attaching means including means for varying the lengths of said strips between said levers and said ring, and

means for rotating said ring for causing said strips and said levers to rotate said vanes.

2. In a fan having a rotor, an inlet to said rotor and a plurality of spin vanes pivoted in said inlet, the combination of levers attached to said vanes, said levers having curved outer surfaces, a ring, a plurality of resilient strips, means attaching said strips adjacent their ends to said surfaces and said ring, said attaching means including means for varying the lengths of said strips between said ring and said levers, and means for rotating said ring for causing said strips and said levers to rotate said vanes.

3. In a fan having a rotor, an inlet to said rotor and a plurality of spin vanes pivoted in said inlet, the combination of levers attached to said vanes, said levers having curved outer surfaces, a ring having a circular inner surface in alignment with said outer surfaces, a plurality of resilient strips, means attaching said strips adjacent their ends to said inner and outer surfaces, said attaching means including means for varying the lengths of said strips between said ring and said levers, and means for rotating said ring for causing said strips and said levers to rotate said vanes.

25

4. In a fan having a rotor, an inlet to said rotor, and a plurality of spin vanes pivoted in said inlet, the pivots of said vanes extending in a circle the plane of which is perpendicular to the axis of the 30 rotor: the combination of a plurality of levers attached to said vanes at said pivots; said levers having their outer ends formed as curved cam surfaces, a ring having a circular inner surface around and aligned radially with said cam surfaces; a plurality of strips of spring metal between and in radial alignment with said inner surface of said ring and said cam surfaces, each of said strips being attached at one end to said ring and at its other end to one of said cam surfaces, and means for rotating said ring for causing said strips and said levers to rotate said vanes towards open and closed positions.

35

5. The combination as claimed in claim 4 in which the cam surfaces are spaced the thicknesses of the strips from the inner surface of the ring when the vanes are in closed positions.
